UNITED STATES PATENT OFFICE.

JOHN R. KELLER, OF GLENSHAW, PENNSYLVANIA.

DESIGN FOR AN ASH TRAY.

Application filed February 9, 1927. Serial No. 20,661. Term of patent 14 years.

To all whom it may concern:

Be it known that I, JOHN R. KELLER, a citizen of the United States, residing at Glenshaw, in the county of Allegheny, State of Pennsylvania, have invented a new, original, and ornamental Design for an Ash Tray, of which the following is a specification, reference being had to the accompanying drawing forming a part thereof.

Figure 1 is a perspective view of an ash tray showing my new design; Fig. 2 is a side

elevational view and Fig. 3 is a cross sectional view.

The important feature of my design consists in the formation of substantially uniform depressions arranged in close formation, extending substantially throughout the inner bottom surface of a tray of any shape.

I claim:

The ornamental design for an ash tray as shown and described.

JOHN R. KELLER.
